[57] **CLAIM**

The ornamental design for a tool box, as shown and described.

DESCRIPTION

FIG. 1 is a perspective view of a tool box showing my new design;

FIG. 2 is a top plan view thereof;

FIG. 3 is a front elevational view thereof;

FIG. 4 is a rear elevational view thereof;

FIG. 5 is a right side elevational view thereof, the left side elevational view being a mirror image; and,

FIG. 6 is a bottom plan view thereof.

The broken line showing of tools in FIG. 1 is for illustrative purposes only and forms no part of the claimed design.
